ESCAPE PREVENTING DEVICE

Dimitri A. Koleshin, 934 Page St., San Francisco, Calif.
Filed May 2, 1960, Ser. No. 26,082
6 Claims. (Cl. 109—6)

The primary object of this invention is to provide an escape preventing device which prevents a robber to escape from a bank, or other building, after he has committed a robbery.

Another object of this invention is to provide a device of the type described which includes a door which closes the entrance into a bank, or a building, when a micro-switch is secretly operated by a bank employee.

Another object of this invention is to provide a device of the type described in which the escape barring door may be opened only from the outside of the bank, or the building, by a switch operable by a special key.

Another object of this invention is to provide a device of the type described which includes a second escape barring door which automatically closes the entrance of a bank, or a building, in case the first door for any causes fails to close completely said entrance.

Another object of this invention is to provide a device of the type described including a special secret micro-switch operable by a teller of the bank, which switch and its operation is undetectable by an outsider.

Other objects and advantages will appear as the specification proceeds and the novel features of the device will be particularly pointed out in the claims hereto annexed.

In this specification and the annexed drawing, the invention is illustrated in the form considered to be the best but it is understood, that the invention is not limited to such form; and it is also to be understood that in and by the claims following the description, it is desired to cover the invention in whatsoever form it may be embodied.

This invention is illustrated in the drawings forming a part of the specification in which:

FIG. 1 is a vertical longitudinal cross-section of an entrance to a bank, or other building showing my device in operation with one door in closed position and the other door in open position.

FIG. 2 is a cross-section along the line 2—2 of FIG. 1.

FIG. 3 is a vertical transverse cross-section of said entrance, showing one door in closed position.

FIG. 4 is a plan view of a currency container.

FIG. 5 is a vertical cross-section along the line 5—5 of FIG. 4 of the currency container.

FIG. 6 is an electric wiring diagram of the device.

FIG. 7 is a fragmentary plan view of the drums showing the operating switches,

FIG. 8 is a diagrammatic back view of the drums showing the spring levers in the normal positions, taken on the line 8—8 of FIG. 7.

FIG. 9 is a diagrammatic back view of the drums showing the spring levers in the different positions.

In detail my device consists of a flexible door 1 which is adapted to close an entrance hall 2 to a bank or other building.

The door 1 consists of a pair of chains 3 moving in guides 5 secured to the side walls 6 of said hall opposite each other.

The chains 3 are connected by a plurality of heavy metal bars 7 of such size and arranged so close to each other, that a man cannot squeeze himself between the same. The lowermost bar 7 carries extending downwardly therefrom to the floor 8 a heavy rubber apron 9.

The door 1 extends upwardly through a ceiling 10 and the upper end thereof is secured to a hexagonal drum 11 of considerable size up which said door is normally

2

wound. The drum 11 is of sufficient width to accommodate said door and carries on its ends pulleys 12 for winding cables 14. The latter extend from said pulleys, over small guide pulleys 15 down and around four pulleys 16 and up and are connected to the ends of the chains 3.

Normally the flexible door 1 is wound around the drum 11. When the latter is rotated in counter-clockwise direction viewing FIG. 1, it winds the cables 14 about the pulleys 12 and at the same time unwinds the door 1, thus moving the door downwardly. To return the door 1 to its initial position, the drum 11 is rotated in the opposite direction. It requires one turn of the drum to unwind a sufficient length of the chains 3 for the rubber apron 9 to reach the floor.

The drum 11 rotates on stub-shafts 20 which are supported by a pair of supports 21. An electric motor 22 through a train of reduction gears 23, 24, 25 and 26 operates said drum, the latter gear being on the stub-shaft 20 near one of the supports 21. A clutch 27 is provided between said gear 26 and the drum 11, and is so arranged that when the door 1 is stopped on its downward movement, said clutch becomes disengaged by pushing said gear away from the drum against the pressure of spring 28 arranged inside said drum on the stub-shaft 20 for pulling the gear toward said drum, as shown in FIG. 3. When the gear 26 is pushed away, it presses upon and actuates a trouble switch 29 for the purpose as shall be hereinafter stated.

A second flexible door 30 is arranged in said entrance hall 2 between the door 1 and the usual entrance door 31. The door 30 is of exactly the same structure as the door 1 including a drum 31, a motor 32, a reduction gear train 33 and pulleys 34 and operating the same way. It is provided as a safeguard, so that in case the door 1 is jammed, or stopped by some means before it reaches the floor, the second door 30 will automatically close the entrance hall 2, as shall be hereinafter stated in detail.

The door 1 is operated by a secret micro-switch which is so arranged and concealed that its operation may not be detected or understood by a robber, and does not create any suspicion, or alarm in him when the teller operates the same during a hold-up.

Many possible places and types of such switches may be employed for that purpose. But after a thorough investigation, I propose that a micro-switch 40 for operating said door 1 be placed in currency drawers 41 of each teller. The drawer usually contains a bill tray 42 divided into a plurality of compartments 43, 44, 45, 46 and 47 for bills of different denominations, such as one dollar, five dollar, ten dollar, twenty dollar and one hundred dollar bills, respectively. Bills in said compartments are held down by spring pressed wire fingers 50 swingable about a transverse shaft 51 extending the width of said tray 42. All fingers 50 are of the same size and configuration. However, the finger 50 in the compartment 47 serves to operate the micro-switch 40 which in turn sets the device in action. Said finger 50 is formed with a hook 52 extending on the other side of said shaft 51 backwardly and downwardly. A spring 53 one end of which is secured to said finger and the other anchored to the floor of said tray, as shown at 54, normally presses said finger downwardly, as shown in FIG. 5. When the finger 50 is down a well concealed small electric light 55 is on, which light is visible only to the teller and not to any outsider. The light indicates that the micro-switch 40 is connected with the source of current. The teller may raise said finger to an angle of about 45 degrees without going over the dead center. He may raise said finger over the angle of 45 degrees, but he will feel that the spring 53 now pulls said finger upwardly. The teller can keep the finger 50 in the latter position without operating the

door 1. But when a holdup man demands to give him all the currency, the teller complies with the request. He lets the finger to rise to the position of 90 degrees, as shown at 56-A, and the hook 52 contacts and operates the micro-switch 40 which is located under said shaft 51. The latter micro-switch turns the light 55 off and actuates the electric motor 22 of the door 1. The motor 22 immediately forces the door 1 downwardly to close the entrance.

The pulley 34 of the second door 30 carries a pin 70 on its outer surface near the periphery thereof which operates a spring lever 71 consisting of two prongs 72 and 73. The lever 71 rocks a shaft 75 to which the same is attached. The shaft 75 operates simultaneously two switches 76 and 77. The switch 76 reverses the motor 32 and the switch 77 cuts off the flow of current to the same, and turns on alarm signals 78 and 79 which may be a siren and a bell respectively. A timing device 81 is included in the electric circuit of said alarm signals to delay the sounding of the alarm signals for ten seconds after the stop switch 77 has been turned on. The lever 71 is operated when the door reaches the floor to set the motor 32 for raising the second door 30.

The pin 70 also operates a third switch 88 by a leaf spring 89 extending over said switch and in the path of said pin. The pin 70 normally presses the spring 89 downwardly to close the switch 88, but when the drum 31 rotates in the clock-wise direction looking at FIG. 8 to close said door, the pin 70 moves upwardly and releases said spring 89, thus opening the switch 88. The latter remains open until the door is lifted and the pin 70 again closes said switch by said spring 89.

The first door 1 has the same arrangement of a pin 95 on the drum 11 which operates a spring lever 96 having two prongs 97 and 98, said lever being secured to a shaft 100. The latter shaft is adapted to operate simultaneously two switches 105 and 106, the first of which reverses the motor and the other cuts off the flow of current to the same, and in addition thereto turns on alarm signals 78 and 79. A third switch 110 is also provided in connection with said door 1 which is normally kept closed by a leaf spring 111 operable by said pin 95. When the door starts to rotate and the pin releases the leaf spring 111, the switch 110 opens.

The spring lever 96 is provided with an extension 115 to which is fulcrumed a secondary lever 116 with freedom of swinging upwardly only. The secondary lever carries a finger 117 fulcrumed to the end thereof. The finger 117 is arranged for swinging downwardly only and is returned to its normal position by a spring 118.

The extension 115, secondary lever 116 and the finger 117 extend to the pulley 34 of the second door 30 and are operated by its pin 70 as follows.

When the door 1 is going down, the spring lever 96 remains in its downward position, as shown in FIG. 8, until it is lifted by the same pin on its upward swing when the door 1 reaches the floor, thus resetting the switch 105 for reversing the rotation of the motor 22.

If the door 1 should stop for some reason on its way down, the second door immediately starts to go down. The pin 70 on its downward motion meets the finger 117 and the secondary lever 116 and swings the same downwardly, thus rocking the shaft 100 and swinging the spring lever 96 upwardly. The shaft 100 operates the switches 105 and 106 the first of which reverses the motor, thus permitting the door to be lifted when the current is delivered to said motor.

Electric Wiring Diagram

The electric wiring diagram shown in FIG. 6, includes a wire 125 connecting a source of electric current with wires 127 and 128 leading to reverse switches 105 and 76, which reverse the flow of current to motors 22 and 30 respectively. The reverse switches 105 and 76 are oper-

ated by the spring levers 96 and 71, as heretofore has been explained in detail.

A wire 126 connects said source of electric current with the contact point 130 of the trouble switch 29. Normally the latter contact point is connected with the contact point 131, which in turn is connected by a wire 132 with a contact point 133 of the switch 110. The latter point is connected with a point 135, when the pressure of the leaf spring keeps the switch closed. If said pressure is released, the point 133 becomes connected with a point 136. From the point 135 current flows through a wire 137 to a point 138 of the micro-switch 40 in a teller's currency drawer. The latter point is normally connected with the point 139 which is connected by a wire 140 to the light 55 and therefrom by a wire 141 to the wire 128 and the source of current.

When the teller operates the switch 40 as heretofore has been explained in detail, the point 138 becomes connected with the point 141, and current runs through wires 142 and 143 to the motor reversing switch 105. The motor 22 turns the drum 11. The pin 95 carried by said drum rises and releases the pressure of the spring 111 from the third switch 110. Thereupon the point 130 is placed in communication with the point 136 which is connected by a wire 145 with the cut-off switch 106, which is closed. The latter switch is connected by a wire 146 to the wire 143 and, hence, to the motor 22. Therefore, the micro-switch 105 need not be held in operative position more than a very short time needed to give the motor 22 a good start. Then the third switch 110 sends the current through the above described circuit.

When the door 1 reaches the floor, the pin 95, after having made an almost complete circle, pushes the lower prong 98 of the spring lever 96 upwardly and rocks the shaft 100. The latter actuates the reverse switch 105 setting the same for the reverse rotation of the motor and the stop switch 106 cuts off the flow of current therethrough. The downward movement of the door 1 stops and the latter remains in such position until a general release switch 150 is operated. At the same time the stop switch 106 turns on current to the wire 151, connected to the timing device 81 and the signal devices 78 and 79. The wire 152 completes this circuit by connecting the latter device to the wire 128.

The switch 150 is operated by a special key which is in possession of one of the employees of the bank. But said switch is located preferably in the hall 2 near the entrance door thereof and out of the reach of any person locked in the bank by the door 1 or 30. When the alarm signals are sounded and the police have arrived, then the key is given to a policeman on the outside through said door 1 or 30. The policeman turns the key and thereby operates the general release switch 150. The latter has a plurality of contact points for various purposes which shall be gradually described hereinafter.

The wire 145 is connected by wire 155 to a contact point 156 of the switch 150. When the latter switch is operated the point 156 is brought in communication with a point 157 which is connected to the wire 143 leading to said reversible switch 105. The motor raises the door 1 up. The pin 95 travels in a counter-clockwise direction and presses the upper prong 97 downwardly, thus pushing the spring lever 96 downwardly, and thereby operating the switches 76, 77 and 88 to reset the same for the initial position hereinbefore described.

If for some reason the door 1 stops before reaching the floor, the gear 26, being pushed away by the clutch 27, as hereinbefore has been described, operates the switch 29 to place the contact point 130 in communication with the point 160 connected by a wire 161 with a point 162 in said general release switch 150 which point is normally in communication with a point 163 in the same switch. The latter point is connected by a wire 165 to a point 166 of the switch 88 of the second motor 32. The latter switch normally keeps the point 166 in communication

with the point 167 which is connected by a wire 168 to the cut-off switch 77. The latter completes the circuit through to a wire 170 and the reversible switch 76. The motor 32 closes the second door 30. When the door 30 reaches the floor, the pin 70, through the spring lever 71, operates the switches 76 and 77, reversing the switch 76, cutting the motor off and turning on the alarm devices 78 and 79. A wire 175 connects said switch 77 with the wire 151 for the purpose of operating said devices.

The second door 30 is also raised by the operation of the general release switch 150. When the pressure of the spring 89 on the switch 88 is released, the point 167 of said switch becomes connected with a point 178. When the general release switch 150 is operated, the following circuit is established: from wire 126 by wire 179 to the point 178, point 157, wire 168, a wire 180 to points 181 and 182 in said general release switch, which become closed, by a wire 183 to the wire 170 and the motor 32, thus raising the door 30.

At the same time the first door 1, which is partially closed, is raised in the following manner: current runs from the wire 26 to the point 130, point 169, a wire 185 to points 186 and 187 of the general release switch; line 188 to the line 143 and the motor 22, thus raising the door 1.

I claim:

1. An escape preventing device for a building, having an entrance hall with a floor, comprising a first door normally located above said hall, means for lowering said door to said floor to close an area in said building, means for raising said door, a second door arranged in spaced relation to the first door above said hall, means for lowering and raising the second door, means associated with the first door for actuating the last mentioned means to lower the second door when the first door fails to reach said floor, means located within said area for actuating the means for lowering the first door, and means outside of said area for actuating the means for raising said doors.

2. An escape preventing device for a building, having an entrance hall with a floor, comprising a first door and a second door normally located above said hall, each door having an electric motor for lowering said doors to said floor to close an area in said building and for raising said doors above said hall, a switch located inside of said area for actuating the motor of the first door to lower the latter to the floor, means associated with the motors for actuating the second motor for lowering the second door only if the first door fails to reach the floor, and means outside said area for actuating said motors for raising said doors.

3. An escape preventing device for a building, having an entrance hall with a floor, comprising a first door located above said hall, an electric motor for lowering said door to the floor of said hall to close an area in said building, and for raising said first door; a second door arranged above said hall in close vicinity of the first door, a second electric motor for lowering said second door to said floor and for raising the same; means for reversing the direction of rotation of the first motor and means for stopping the same; a first lever associated with the first door for actuating the last two mentioned means when the first door reaches the floor; means for reversing the direction of rotation of the second motor and means for stopping the same; a second lever associated with the second door for actuating the last two mentioned means when second door reaches the floor; means associated with the first door for actuating the second motor when the first door on its downward motion fails to reach the floor, said first lever having an extension for operating said first lever by the movement of the second door; a secret switch within said building for actuating the first

motor for closing the first door; and a general release switch for raising the first and the second doors.

4. In an escape preventing device of the class described, a combination of two flexible doors arranged above an entrance into a building, comprising a first door, a first drum upon which said first door is normally wound, a first electric motor for unwinding the drum and lowering said first door to the floor of said entrance and for winding said first drum and raising the first door; a switch for reversing the rotation of said first motor and a switch for cutting the motor off, means operable by said drum for simultaneously operating said two switches when the first door reaches the floor of an entrance; a second door, a second drum upon which the latter door is wound, a second electric motor for lowering and raising said second door, a switch for reversing the rotation of said second motor, a switch for cutting the last mentioned motor off, means operable by said second drum for simultaneously operating said last mentioned two switches when the second door reaches the floor of the entrance; means operable by the second drum and associated with the means operable by the first drum for simultaneously operating said first mentioned switches for reversing the rotation of the first motor and for cutting the same off if the first door fails to reach said floor, and means for actuating said second motor for lowering the second door when the first door fails to reach said floor.

5. In an escape preventing device of the class described, a combination of two doors arranged above an entrance into a building in spaced relation to each other, an electric motor for raising and lowering each door for closing an area in said building to prevent egress therefrom; means associated with each motor for stopping the same when the respective door reaches the floor; a switch inside of said area for actuating the motor of one door to lower the same to the floor; means associated with the motor of the last mentioned door for actuating the motor of the second door for lowering the same to the floor, whenever the first door fails to reach the floor; means for reversing the rotation of said motors; and a means for actuating said motors for raising said doors.

6. In an escape preventing device of the class described, a combination of two flexible doors arranged above an entrance into a building in spaced relation to each other comprising a first flexible door, a first drum for winding said first door, a first electric motor for lowering said first door to the floor of said entrance for barring the exit from an area in said building; means associated with the first mentioned drum for stopping said first motor and for reversing its rotation when the first door reaches the floor; a second flexible door, a second drum for winding said second door, a second electric motor for lowering said second door and for raising the same, means for stopping said motor and for reversing its rotation when the second door reaches the floor; means for stopping the first motor and means for actuating the second motor for lowering the second door when the first door fails to reach said floor.
